UNITED STATES PATENT OFFICE.

JOHN P. E. NEILSON, OF QUINCY, MASSACHUSETTS, ASSIGNOR TO MEISEL PRESS MANUFACTURING COMPANY, OF BOSTON, MASSACHUSETTS, A CORPORATION OF MASSACHUSETTS.

SHEET CONTROL FOR PRINTING PRESSES AND THE LIKE.

Application filed March 4, 1922. Serial No. 541,206.

To all whom it may concern:

Be it known that I, JOHN P. E. NEILSON, a citizen of the United States, and a resident of Quincy, county of Norfolk, and State of Massachusetts, have invented an Improvement in Sheet Controls for Printing Presses and the like, of which the following description, in connection with the accompanying drawings, is a specification, like characters on the drawings representing like parts.

This invention relates to means for controlling the feed of sheets of paper as, for example, in printing presses. The object is to provide a simple and convenient mechanism whereby a paper sheet may be spread out perfectly smooth as, for example, in advancing it over a support to a printing couple to be printed upon. This action is particularly necessary in the case of multi-color presses in which one impression is made over another and any inaccuracy of feeding or unevenness of the sheet would destroy the register. While my invention may be embodied in various forms it is markedly useful in connection with a press of the type shown in the patent to Charles A. Meisel, No. 1,399,360, dated December 6, 1891, and for purposes of illustration I have here shown an embodiment thereof as applied to such a press.

This specific embodiment of my invention will best be understood by reference to the following description taken in connection with the accompanying drawings, wherein:

Fig. 1 is a diagrammatic view of certain elements of a ring gear, multi-color, multi-couple press of the type shown in the patent referred to;

Fig. 2 is a section on the line 2—2 of Fig. 1 on an enlarged scale;

Fig. 3 is a broken section taken in a plane parallel to one of the ring gears and on an enlarged scale; and

Fig. 4 is a section on the line 4—4 of Fig. 3.

Details of construction of a ring gear press of the type referred to herein are disclosed in the above mentioned patent of Charles A. Meisel. The essential elements necessary to an understanding of my invention as applied to a press of this type are sufficiently illustrated in the accompanying drawings. Such a press may embody a sheet carrier comprising (see Fig. 2) two ring

gears 7 supported in parallelism on the frame of the machine (see Fig. 1) by rollers 9 and connected at intervals by gripper bars 11, the whole having somewhat the appearance of a lantern wheel. On rotation of the ring gears the gripper bars 11 sweep through a cylindrical path and carry the paper through a series of rotary printing couples comprising impression cylinders 13 and plate cylinders 15, the contact lines of which correspond to elements of the cylinder, using that word in its geometrical sense. Sheets of paper are delivered to the gripper bars by a suitable feeding mechanism which may embody a cylinder 17 tangent to the cylindrical path exteriorly thereof and a transfer cylinder 19 tangent at the same point interiorly and may be delivered from the press by a transfer cylinder 21 interiorly tangent to the path and a delivery cylinder or similar mechanism 23, all as more fully described in the patent referred to.

To support the sheet as it passes through the printing couples suitable fixed supporting surfaces 25 may be provided which correspond to segments of a cylinder. The gripper bars travel around the cylindrical path at a fixed linear speed and the paper, supported throughout in this path by the supports 25, is moved at a fixed speed during the printing operation with all portions thereof at an unvarying curvature. It will be understood that these conditions are most favorable for accurate registry of successive impressions by the printing couples provided that the sheet is extended smoothly in the cylindrical surface and held against wrinkle or vibration. My invention as applied to a press of this type insures such action.

In accordance with my invention the sheet held by one of the gripper bars 11 is tensioned rearwardly therefrom and ironed out over the supports 25 and for this purpose the left hand edge of such support, viewing Fig. 1, may be utilized as the paper is drawn thereon gradually to iron out and tension the sheet against a yielding resistance. For this purpose I may utilize suitable tapes or other strand-like elements 27 moving with the sheet and adapted to make contact with the outer surface thereof at margins or other portions of the sheet which are not to receive an impression. These tapes 27 are se-

cured to the gripper bar and are resiliently extended therefrom, in the present instance by being secured to a spring roller 29 carried by and extending between the ring gears 7 at a suitable distance rearwardly from the gripper bar. The spring roller tends to wind up the tapes 27 and withdraw them to the position shown at the bottom of Fig. 1 where they extend chord-like across the cylinder. The gripper bar, advancing clockwise in the figure, receives the sheet at the inner side of the tapes 27 from the transfer cylinder 19. After passing through the first couple it is drawn over the cylindrical supporting surface 25 which obviously must displace the tapes 27 outwardly until they lie in the surface of the cylinder, the roller 29 yielding to permit them to be drawn out. The sheet is drawn forward under the tapes 27 over this surface which bends it to convex form against the resistance of the tapes and gradually shapes the sheet and the tapes to the arc of a circle, ironing out the sheet from its forward end adjacent the gripper bar to its free following end and smoothing it perfectly over the accurately formed surface 25. The tapes 27 yieldingly clamp each successive portion of the sheet against the surface 25 as it passes thereover and they hold it as a whole smoothly and firmly on the successive surfaces as the printing operation proceeds but always, by the cooperation of such surfaces 25, smoothing it and tensioning it rearwardly from its leading edge where it is held by the gripper 11.

Referring to Figs. 3 and 4, I will next describe a suitable method of securing the tapes or similar strands 27. It will be understood that the tapes must make contact with the sheet at points where no printing is to take place and these unprinted margins may occur at different places. It is therefore desirable to mount the tapes so that they may be shifted laterally as desired. Herein (see Fig. 3) the tape passes under the rear edge 31 of the gripper bar 11 on which the gripper fingers close, passes over the rock shaft which operates these fingers, and passes through a slot 33 in the front wall of the gripper bar where it may be toggled or otherwise suitably secured. I have found it convenient to utilize a section of a helical spring 35 as a toggle for securing the tape. Obviously the tape may be shifted laterally in the slot 33.

Referring to Figs. 3 and 4, the roller 29 may be provided with a diametrical slot 37 and, as best shown in Fig. 4, the end of the tape may be passed through this slot and the end caught underneath a turn of the tape encircling the roller, this efficiently securing it in position in a manner readily cast off, if desired. The slot 37 provides for lateral adjustment of the tapes.

Referring to Fig. 4, the roller 29 there

shown is mounted on trunnions 39 in the brackets 41 carried by the ring gears 7 and suitable helical springs 43 secured at one end to the brackets encircle these trunnions and the other ends engage with the castellated end portions 45 of the rollers which provide for an adjustment of the spring tension. The springs tend to rotate the roller 29 clockwise, viewing Fig. 3, and thus to wind up the tapes 27 so that when not displaced by the supporting surfaces 25 they assume the chord-like position shown at the bottom of Fig. 1.

Having thus described in detail my invention as applied to the particular form of printing press here shown, the principles exemplified thereby which I claim as new and desire to secure by Letters Patent I shall express in the following claims.

Claims:

1. In a device of the class described, a sheet support, means for drawing a sheet forward over said support by engagement with the leading edge thereof and yieldable means extending rearwardly over the sheet from said drawing means and adapted to be displaced by the support thereby to smooth the sheet over the support. 90

2. In a device of the class described, a sheet support, means for drawing a sheet forward over said support by engagement with the leading edge thereof and yieldably stretched strands extending rearwardly from said drawing means over the sheet and adapted to be bent outwardly by said support. 95

3. In a device of the class described, a convex sheet support, means for drawing a sheet forward over said support and strands extending rearwardly from said drawing means normally resiliently tending to assume a position corresponding to a chord of said support. 105

4. In a device of the class described, a convex sheet support, means for drawing a sheet forward over said support comprising a gripper bar engaging the leading edge of the sheet, a bar at the rear thereof and strands yieldably stretched between the bars. 110

5. In a device of the class described, a convex sheet support, means for drawing a sheet forward over said support comprising a gripper bar engaging the leading edge of the sheet, a spring roller at the rear thereof and strands extending between the bar and the roller. 115

6. In combination with a device for advancing a sheet by engagement with a leading edge thereof, a convex member to engage one face of the sheet, a member resiliently stretched in the general direction of travel of the sheet, one of said members moving with the sheet and the other being stationary, the convex member serving to displace the stretched member as the two pass 125

whereby to smooth the sheet over the convex member.

7. In combination with a device for advancing a sheet by engagement with a leading edge thereof, a convex surface over which the sheet is moved, and a yieldably extended strand traveling with the sheet, the points between which it is tensioned located substantially to coincide with said surface.

8. A press comprising printing couples ranged about a cylindrical path, supporting surfaces corresponding to segments of the cylinder, a gripper movable over the cylindrical surface to draw a sheet thereover and resilient devices moving with the sheet tending to assume a position located inwardly of said surface.

9. A press comprising printing couples ranged about a cylindrical path, supporting surfaces corresponding to segments of the cylinder, a gripper movable over the cylindrical surface to draw a sheet thereover and resiliently extended strands moving with the sheet normally tending to assume the position of chords to said surface.

10. In combination with means for drawing a sheet forwardly by the leading edge thereof, a support adapted to engage a face of the sheet in its travel and means to smooth the sheet comprising flexible means tensioned rearwardly from said drawing means over the opposite face of the sheet and adapted to be bent by said support.

11. A press comprising a plurality of rotary couples the lines of contact of which correspond to elements of a cylinder, intermediate supporting surfaces in the form of cylindrical segments, rotary rings at the bases of the cylinder, bars connecting them over the cylindrical surface, and flexible elements yieldably stretched between pairs of the bars.

12. A press comprising a plurality of rotary couples the lines of contact of which correspond to elements of a cylinder, intermediate supporting surfaces in the form of cylindrical segments, rotary rings at the bases of the cylinder, bars connecting them over the cylindrical surface, certain bars having gripper means for engaging a sheet, and flexible elements extending from said bars and secured to a following bar by resilient take up means.

13. The method of smoothing a sheet characterized by drawing it over a support while subject to the resistance of a yieldable element extended over a face thereof and moving therewith.

14. The method of smoothing a sheet

characterized by shaping it to a convex surface by drawing it thereover while subject to the resistance to such shaping afforded by a yieldable element extended over a face thereof and moving therewith.

15. In combination with means moving through a curvilinear path drawing a sheet forward by the leading edge thereof a flexible element yieldably extended rearwardly from said means and tending to assume the position of a chord of such path and means inwardly of said path having a portion lying therein to displace said element as it passes thereover.

16. A press comprising a gripper bar movable in an orbital path, flexible strands yieldably extended rearwardly from the bar, an interiorly disposed element having a portion presented in said path and sheet feeding means comprising an element disposed interiorly of the orbit directly delivering the sheet to said gripper bar whereby the sheet passes between said strands and said interiorly disposed element.

17. In a device of the class described, a convex sheet support, means for drawing a sheet forward over said support comprising a gripper bar engaging the leading edge of the sheet, a bar at the rear thereof and strands yieldably stretched between the bars and shiftable therewith.

18. In a press a convex sheet support and means for advancing a sheet over the support for printing comprising a slotted gripper bar engaging the leading edge of the sheet, a slotted spring roller at the rear thereof and strands extending between bar and roller having their ends secured in said slots.

19. In a device of the class described, a sheet support, means for drawing a sheet forward over said support by engagement with the leading edge thereof and yieldable means moving with said sheet and extending over the same adapted to be displaced by the support thereby to smooth the sheet over the support.

20. In a device of the class described a convex sheet support, means for drawing a sheet forward over said support by engagement with the leading edge thereof, yieldable means overlying the sheet and traveling therewith normally tending to press the sheet inwardly and adapted to be displaced outwardly and shaped to the form of said support to smooth the sheet thereover.

In testimony whereof I have signed my name to this specification.

JOHN P. E. NEILSON.
